UNITED STATES PATENT OFFICE.

ABRAM C. MOTT AND JOHN K. McLAUGHLIN, OF PHILADELPHIA, PA., AS-SIGNORS TO THE ABRAM COX STOVE COMPANY, OF SAME PLACE.

DESIGN FOR A STOVE OR RANGE.

SPECIFICATION forming part of Design No. 16,586, dated March 23, 1886.

Application filed February 1, 1886. Serial No. 190,553. Term of patent 14 years.

To all whom it may concern:

Be it known that we, ABRAM C. MOTT and JOHN K. McLAUGHLIN, citizens of the United States, residing in Philadelphia, Pennsylvania, have invented a certain Design for Stove or Range, of which the following is a specification.

Our design for the door and side plate of a stove or range is fully shown in the accompanying photographic illustration; and it consists, essentially, of a raised panel, A, extending over the door B and part of the side plate B'. The panel is represented as rectangular and comprising an outer frame-like portion, 15 D, around the margin, with two raised bulbs, a a, and an intermediate ornamental plate, b, within the frame. This frame-like portion D comprises parallel flutings d, broken at the corners and midway of the length of the frame 20 by shell-like ornaments e.

We claim—

1. The herein-described design for the door and side plate of a stove or range, said design comprising a raised panel extending over the door and part of the side plate, substantially 25 as shown and set forth.

2. The herein-described design for a stove, said design comprising a raised panel extending over the door and part of the side plate, and having a frame-like outer portion, with 30 flutings d and ornaments e, substantially as shown and specified.

3. The herein-described design for a stove or range panel, comprising a frame-like outer portion of flutings, d, and ornaments e, with 35 raised bulbs a, and an intermediate ornamental plate, b, within the said outer portion, substantially as shown and set forth.

In testimony whereof we have signed our names to this specification in the presence of 40 two subscribing witnesses.
